UNITED STATES PATENT OFFICE.

EDWARD T. DUMAS, OF CHICAGO, ILLINOIS.

RAILROAD-CROSSING.

No. 846,190.

Specification of Letters Patent.

Patented March 5, 1907.

Application filed December 17, 1906. Serial No. 348,306.

To all whom it may concern:

Be it known that I, EDWARD T. DUMAS, a citizen of the United States, residing at Chicago, in the county of Cook and State of Illinois, have invented a certain new and useful Improvement in Railroad-Crossings, of which the following is a specification.

My invention relates to railroad-crossings, and has for its object to provide new and improved devices and arrangements in constructions of that character.

The invention is illustrated in the accompanying drawings, wherein—

Figure 1 is a plan view of the crossing constructed according to my invention; Fig. 2, a detail plan of one of the rail-chairs; Fig. 3, an inverted plan of the same; Fig. 4, a section on line 4 4 of Fig. 2; Fig. 5, a section on line 5 5 of Fig. 1, and Fig. 6 a detail plan showing a modification.

Like letters of reference indicate like parts in all the drawings.

My invention relates particularly to railroad-crossings comprising fixed track-rails, fixed crossing-rails with adjacent ends spaced apart, and movable rail-sections operating in sets to connect the fixed track-rails with the fixed crossing-rails.

More particularly the invention relates to means for holding the outer ends of the movable rail-sections constantly in engagement with the fixed track-rails and guiding the movement of the movable rail-sections. Ordinarily the track-rails will be bent to form knees and the movable rail-sections provided with switch-points working on these knees.

It is another object of my invention to provide a construction whereby the relation between the bend of the knee and the switch-point will remain constant even should the rails creep, as it is well known they sometimes do, and thus to obviate the danger of the switch-point projecting beyond the knee. The likelihood of this latter happening is one of the reasons why earlier crossings of this character have not come into general use.

The invention consists in such further new and improved devices as will be described in the accompanying specification.

The letters A represent the fixed track-rails, which are preferably bent at their extremities to form the knees A. B B B are the fixed central crossing-rails with their ends spaced apart, as shown.

The letter C represents the movable rail-sections, which are of course operated in sets of four, so as to close the gaps between pairs of the fixed track-rails and their respective crossing-rails. The rail-sections C are preferably formed with switch-points C', the inner ends being squared, so as to abut against the squared ends of the crossing-rails. In Fig. 6, however, I have shown a modified construction providing for the beveling of the crossing-rails (here indicated by the letters B' B') of the movable rail-sections (here designated by the letters C² C².) The latter arrangement results in a closer joint, but the rail-sections have to be moved a greater distance.

The track-rails are laid upon ties or sleepers in the ordinary manner, but their inner extremities are fixed in guides so related to the bends of the knees that a creeping of the rails results, as it were, in carrying the bend farther up the rail from its extremity as the latter creeps toward the crossing, thus maintaining a constant relation between the bend and the switch-points. These guides also serve to hold the switch-points in close contact with the fixed track-rails in both open and closed positions, the movable sections and the guides being preferably so constructed as to draw the switch-points, if anything, closer to the fixed rails when they are in abutment with the crossing-rails. I have shown these guides as consisting of plates D, secured to the ties by the spikes D' D', as shown in Fig. 5, the plates having undercut grooves to receive the flanges A² of the rails and the flanges C³ of the rail-sections C, the latter riding over the flanges of the fixed rails and preferably widening toward their extremities, so as to act as wedges to hold the switch-points against the knees of the fixed rails. To prevent the possibility of the switch-points forming obstructions in the way of the wheels, the spread of the fixed rails begins a trifle in advance of the ends of the switch-points when the movable sections are in their closed positions.

In order to insure maintaining the fixed rails and movable sections in proper relation to each other, I prefer to employ a second set of guides E at the inner extremity of the knees, these being similar to the guide-plates D. I also provide means for supporting the fixed central crossing-rails and means for guiding the inner ends of the movable sections. The

details of these devices are shown in Figs. 2 to 4, inclusive.

F E F F are sleepers, which are preferably mitered and form a square structure at the center of the crossing. They may be secured to the ties by bolts or spikes. The crossing-rails B B B B are preferably riveted to these sleepers with their ends seated in the chairs G. These chairs consist of square plates secured to the sleepers F by the bolts G' and provided with four undercut grooves meeting in the center. In two of these grooves G² G² are the ends of the fixed crossing-rails, and the other two, G³ G³, receive the ends of the movable rail-sections. The chairs, therefore, serve to bind together the sleepers F F F F to aid in holding the central crossing-rails rigid and to form guideways for the movable rail-sections.

20 The rail-sections may be moved by any preferred form of apparatus. I have shown means for moving the two opposite pairs of movable sections in unison. H represents a rod from the switch-tower, on which is pivoted a bell-crank H', mounted on a clevis-plate H², secured in the cement block H³ or to some other solid part of the road-bed. At the other end of the bell-crank is a cross-rod H⁴, connected with a pivoted bell-crank H⁵, to the other arm of which is an operating-rod H⁶, pivoted to the plate H⁷, which has an extension-rod guided in guides H⁸ H⁹ on the ties, to which plate H⁷ are pivoted the two rods H¹⁰ H¹¹, connected at their inner ends to the movable rail-sections. At the end of the rod H¹⁰ is another bell-crank H¹⁰, cross-rod H¹¹, bell-crank H¹², rod H¹³, guided at H¹⁴ H¹⁴, to which is connected in a manner similar to the connections of rod H⁶ a pair of rods H¹⁵ H¹⁶, connected to the pair of movable rail-sections opposite the pair operated by the rods H¹⁰ H¹¹.

The sets of movable rail-sections of the other track are moved by a similar apparatus operated by a rod J, going to the switch-tower, one pair of movable sections being connected with this rod by bell-crank J', cross-rod J², bell-crank J³, cross-rod J⁴, bell-crank J⁵, operating-rod J⁶, guided at J' J', and having the diagonal rods J⁸ J⁸ connected to the rail-sections, the other pair being connected to rod J by bell-crank J⁹, operating-rod J¹⁰, guided at J¹¹ J¹¹ and having the pair of diagonal rods J¹² J¹².

55 I wish it to be understood that I do not desire to limit myself to the particular devices and constructions herein described, as obvious modifications will occur to persons skilled in the art.

60 The use and operation of my device are as follows: Normally the several pairs of movable rail-sections will be drawn away from the central crossing-rails. Before the train is to pass over the crossing the movable rail-sections associated with the track on which

the train is moving will be slid down the knees of the fixed rails until their ends abut the ends of the fixed central crossing-rails. The movement of the rail-sections is substantially longitudinal, the switch-points being pressed close against the knees of the track-rails by the engagement of the flanges with the guide-plates. At the same time the inner knees of the movable sections will be guided with certainty into contact with the fixed crossing-rails. Absolute certainty of operation is the requisite in constructions of this character. There have been many devices of one sort or another in which it has been sought by means of movable rail-sections to bridge over the gaps in crossings of this sort; but these devices have not come into use in part because of the complicated nature of the mechanisms by which it was sought to solve the problem, but more particularly because these devices could not be counted upon to operate with perfect certainty and perfect accuracy. It would be fatal, for example, to have the switch-points of the movable sections extend out beyond the bend of the track-rails, a contingency likely to arise through the creeping of the rails unless some provision be made to maintain the relation constant. Further, it is undesirable to have any lateral motion of the movable sections, as that would be sure to result in a loose contact between the switch-points and the track-rails likely to cause the derailing of the train. It is perhaps equally necessary that the central short sections should be firmly anchored to the road-bed and that the connection between these fixed rails and the movable sections should be perfectly accurate.

It must be understood that the wear and tear upon apparatus of this sort necessarily composed of short and somewhat light parts of rails subjected to the strain incident to heavy traffic is very great.

The apparatus of my invention is designed to give a simple, accurate, and durable railroad-crossing which will meet all of the requirements above mentioned.

I claim—

1. In a railroad-crossing, the combination of fixed track-rails with fixed crossing-rails having their adjacent ends spaced apart and longitudinally-movable rail-sections to connect the track and crossing rails, and guides at each end of the movable rail-sections with which the rail-sections are always in engagement to guide the movable rail-sections into contact with the fixed track-rails at the proper points thereon.

2. In a railroad-crossing the combination of fixed track-rails having their ends bent outwardly with fixed crossing-rails having their adjacent ends spaced apart and longitudinally-movable rail-sections having switch-points to connect the track and cross-

ing rails, and guides to guide the movable rail-sections into contact with the fixed track-rails at proper points thereon.

3. In a railroad-crossing, the combination of fixed track-rails, having their ends bent outwardly with fixed crossing-rails having their adjacent ends spaced apart and longitudinally-movable rail-sections having switch-points to connect the track and crossing rails, and guides adjacent the bent portions of the fixed track-rails to receive said rails and to receive and form bearings for the movable rail-sections.

4. In a railroad-crossing, the combination of fixed track-rails having their ends bent outwardly with fixed crossing-rails having their adjacent ends spaced apart and longitudinally-movable rail-sections having switch-points to connect the track and crossing rails, and a pair of guides for each fixed track-rail to receive the bent end of the same and to receive and form a bearing for its respective movable rail-section.

5. In a railroad-crossing, the combination of fixed track-rails having their ends bent outwardly with fixed crossing-rails having their adjacent ends spaced apart and longitudinally-movable rail-sections having switch-points and flanges adjacent thereto, to connect the track and crossing rails, and guide-plates having slots to receive the flanges of the fixed track-rails and of the movable rail-sections.

6. In a railroad-crossing, the combination of fixed track-rails having their ends bent outwardly with fixed crossing-rails having their adjacent ends spaced apart and longitudinally-movable rail-sections having switch-points and wedge-shaped flanges adjacent thereto to connect the track and crossing rails, and guide-plates having slots to receive the flanges of the fixed track-rails and of the movable rail-sections.

7. In a device of the character described, the combination of fixed rails having bends therein with movable rail-sections terminating in switch-points lying along the bends of the fixed rails and guide-plates to receive the bent portions of the fixed rails and the switch-points so as to maintain the latter in constant relation to the bends of the former.

8. In a railroad-crossing, the combination of fixed track-rails with fixed crossing-rails having their adjacent ends spaced apart and longitudinally-movable rail-sections to connect the track and crossing rails, and chairs associated with the fixed crossing-rails to receive and guide the ends of the movable rail-sections into contact with said fixed crossing-rails.

9. In a railroad-crossing, the combination of fixed track-rails with fixed crossing-rails having their adjacent ends spaced apart, longitudinally-movable rail-sections to connect the track and crossing rails, and chairs

associated with the crossing-rails and having slots in their upper faces to receive and guide the inner ends of the movable rail-sections.

10. In a railroad-crossing, the combination of fixed track-rails with fixed crossing-rails having their adjacent ends spaced apart, longitudinally-movable rail-sections to connect the track and crossing rails, and chairs associated with the crossing-rails and having slots in their upper faces in which the crossing-rails are seated and which receive and guide the inner ends of the movable rail-sections.

11. In a railroad-crossing, the combination of fixed track-rails with fixed crossing-rails having their adjacent ends spaced apart, sleepers on which the crossing-rails are mounted, chairs connecting the ends of said sleepers and having slots in their upper faces meeting in the middle and longitudinally-movable rail-sections to connect the track and crossing rail, inner ends of said rail-sections seated and movable in the slots in said chairs.

12. In a device of the character described, the combination of a fixed track-rail with a rail-section movable longitudinally with respect to the track-rail, one of said elements having a switch-point lying along the other, and rigid means fixed to a stationary part of the road-bed for holding said switch-point pressed against the other rail in all positions of the movable section.

13. In a device of the character described, the combination of a fixed track-rail, with a rail-section movable longitudinally with respect to the track-rail and having a switch-point lying along the fixed rail, and rigid means fixed to a stationary part of the road-bed for holding said switch-point pressed against the fixed rail in all positions of the movable section.

14. In a device of the character described, the combination of a fixed track-rail with a rail-section movable longitudinally with respect to the track-rail and having a switch-point lying along the fixed rail and a guiding-flange, and rigid means fixed to a stationary part of the road-bed and engaging with the flange for holding said switch-point pressed against the fixed rail in all positions of the movable section.

15. In a device of the character described, the combination of a fixed track-rail with a rail-section movable longitudinally with respect to the track-rail and having a switch-point lying along the fixed rail and a guiding-flange, and means fixed to the stationary part of the road-bed having a part overlapping the flange to keep said switch-point at the proper level and pressed against the fixed rail in all positions of the movable section.

16. In a device of the character described, the combination of a fixed track-rail with a rail-section movable longitudinally with re-

spect to the track-rail and having a switch-point lying along the fixed rail and a wedge-shaped flange, and means fixed to a stationary part of the road-bed having a part coacting with the wedge to force the switch-point into contact with the fixed rail.

17. In a device of the character described, the combination of a fixed track-rail with a rail-section movable longitudinally with respect to the track-rail and having a switch-point lying along the fixed rail and a wedge-shaped flange, and an undercut slotted guide-plate fixed to a stationary part of the road-bed having a part to receive said flange.

18. In a device of the character described, the combination of a fixed track-rail having a bend therein, with guiding means fixed to a stationary part of the road-bed to engage with the rail near its bend so as to keep the bend of the rail at the same place on the track regardless of the creep of the rail.

19. In a device of the character described, the combination of a fixed track-rail having a bend therein, with two guide-plates having slots to receive the flange of the rail fixed to stationary parts of the road-bed, said guide-plates adapted to keep the bend of the rail at

the same place on the track regardless of the creep of the rail.

20. In a device of the character described, the combination of two rails, at least one of said rails being movable and one of said rails having a switch-point adapted to lie along the other rail, with rigid means fixed to a stationary part of the road-bed for keeping said switch-point constantly in contact with the other rail in all positions of said rails relative to each other.

21. In a device of the character described, the combination of two rails, at least one of said rails being movable and one of said rails having a switch-point adapted to lie along the other rail, the flange of at least one of said rails being wedge-shaped, with a guide-plate having a slot therein to receive the flanges of said rails, said guide-plate adapted to keep said switch-point constantly in contact with the other rail in all positions of said rails relative to each other.

EDWARD T. DUMAS.
